E. PROBST

ELECTRIC HEATING UNIT

Filed March 22, 1923

Inventor:
Emil Probst:
by *Alexander S. Lant*
His Attorney.

UNITED STATES PATENT OFFICE.

EMIL PROBST, OF CHARLOTTENBURG, GERMANY, ASSIGNOR TO GENERAL ELECTRIC COMPANY, A CORPORATION OF NEW YORK.

ELECTRIC HEATING UNIT.

Application filed March 22, 1923. Serial No. 626,970.

To all whom it may concern:

Be it known that I, EMIL PROBST, a citizen of the German Republic, residing at Charlottenburg, Germany, have invented 5 certain new and useful Improvements in Electric Heating Units, of which the following is a specification.

My invention relates to electric heating units, and has for its object to make it possible to load the heating resistance specially 10 high, and therewith to obtain at the same time a specially great radiating effect.

According to my invention the heating resistance is arranged in a spirally bent 15 quartz tube, which is closed and filled with an indifferent gas. Such a heating unit is particularly adapted for use in radiant heaters, or for like purposes.

In the drawing is shown one illustrative 20 embodiment of my invention.

Referring to the drawing, *a* is a spirally bent quartz tube, *b* a heating resistance conductor situated therein. The leading-in wires for the heating resistance *b* are fused 25 in at the two ends of the quartz tube *a*, so that the quartz tube *a* is closed perfectly airtight. This sealing of the ends of the quartz tube *a* around the leading-in wires may be accomplished in any suitable manner, for

example, by means of the blended seal process disclosed in United States Patent No. 1,173,688 to Elihu Thomson. The closed tube *a* is filled with a gas which is indifferent as regards the resistance wire *b*, which gas causes a good transmission of heat to 30 the quartz tube *a*. As a filling gas, hydrogen or nitrogen are suitable.

The quartz tube *a* itself may assume a comparatively high temperature without danger of its being destroyed or of its becoming 35 permeable to gas.

What I claim as new and desire to secure by Letters Patent of the United States, is,—

1. An electric heating unit comprising a spirally bent quartz tube, said tube being 40 closed and filled with an indifferent gas, and a resistance conductor extending through said tube.

2. An electric heating unit comprising a spirally bent quartz tube, a resistance conductor in said tube extending throughout 45 its length, and leading-in wires for said resistance conductor, said tube having its ends sealed around said leading-in wires and being filled with an indifferent gas. 50

In witness whereof, I have hereunto set my hand this 27th day of February, 1923.

EMIL PROBST.
